MEANS FOR FORMING PLEATS

Alexander McD. Hess, New York, N. Y.

Application December 8, 1945, Serial No. 633,640

1 Claim. (Cl. 160—348)

1

This invention relates to headings for curtains, drapes or other fabrics whereby pleats may be readily formed.

The main object of the invention is to provide a structure whereby the pleating of a fabric is readily and simply accomplished.

A further object of the invention is to provide improved structures of pleated fabrics whereby the pleating may be readily accomplished by the housewife or others.

A further object of the invention is to provide an improved construction of strips or loops whereby the curtain or drape may be suspended by a rod or pole.

Other and ancillary objects of the invention will appear hereinafter.

In the accompanying drawings which illustrate the invention:

Fig. 1 is a front elevation, partly broken away, of an improved arrangement of pleating tape and supporting straps for a curtain; Fig. 2 is an end elevation of the apparatus of Fig. 1; Fig. 3 is a partial section on the line III—III of Fig. 1, but with the parts in pleated position; Fig. 4 is a face view, partly broken away of another form of pleating tape; Fig. 5 is a top plan view, partly broken away, of the pleating tape as shown in Fig. 4 adjusted to a pleating position and showing the relation of a supporting rod or pole thereto; Fig. 6 is a front elevational view, partly broken away, showing a modified form of pleating heading applied to a drape; Fig. 7 is a section on the line VII—VII of Fig. 6; Fig. 8 is a perspective view showing pleats formed in the drape having the head as shown in Fig. 6; Fig. 9 is a transverse section of a strip 30 showing the application of a covering material thereto; Fig. 10 is a front face view, partly broken away, of a still further form of pleating heading applied to a drape; Fig. 11 is a section on the line XI—XI of Fig. 10 and Fig. 12 is a perspective view showing the formation of the pleats with the pleating heading as shown in Fig. 10.

Referring to Figs. 1 and 2 of the drawings, a tape 13 of buckram having equally spaced metal snap fastening members 14, these members being alternately male and female, is provided. Upon the drape 15, such as a curtain, is sewed or looped cord 16, this looped cord being sewed to the drape along the line 17 and also along the line 18, the sewing along the line 17 and that along the line 18 respectively may be continuous or may be discontinuous as shown, the looped portion 19 between the two lines 17 and 18 form in effect straps which are secured at their ends to the drape 15.

2

The tape 13 with its snap fastening members is inserted beneath these straps and secured to the drape in such position that the fastening members 14 are located approximately midway between adjacent straps. To pleat the curtain or other fabric, the adjacent male and female fastening members are secured together when the buckram strip or tape and the fabric or drape will be pleated with a strap adjacent the ridges of each pleat at the back of the drape, the last mentioned strap forming means beneath which the curtain rod or pole may be inserted to support the structure in the case of a curtain as shown in Fig. 3.

In Figs. 4 and 5 a tape 20 of buckram or other suitable material having the equally spaced elongated slots 21 may be sewed at its edges 22 and 23 to a drape or fabric such as 15 of Fig. 1. In the case of the structure of Figs. 4 and 5, the portions 24 between the slots form strips at the back of the curtain or other drape, and when adjacent straps 24 are twisted together as shown in Fig. 5 the tape 20 is puckered or pleated and forms a corresponding pucker or pleat in the drape 25. The straps may be held in twisted condition by inserting between them the supporting rod or pole 26 as indicated in Fig. 5.

Referring to Figs. 6, 7 and 8, there is therein shown a drapery or curtain heading comprising a series of vertical straps 30 of buckram or other suitably stiffened cloth. These straps have gaps or spaces 31 between them and are secured together so as to form a tape by being sewed to the strips 32 and 33 along the seam lines 34 and 35. These strips 32 and 33 may be of the same material as the straps 30.

The tape formed of the straps 30 secured to the strips 32 and 33 as described, may be secured to the upper edge of a curtain or drape 36 by sewing the strips 32 and 33 to the drape 36, along the seam lines 37 and 38.

Wherever a pleat or a series of pleats is desired a strap 30, and with it the drape to which it is secured, is bent or creased into one or more pleats 39. This brings into proximity the adjacent straps 30 on each side of the creased or pleated straps, as shown in Fig. 8, and the strips are supported by inserting a curtain rod 40 beneath the uncreased or unpleated straps 30.

While it is usually desirable to have the tape, comprising the straps 30 secured to the strips 32 and 33 independently of the curtain or drape, so that the tape may be made up separately and applied to any drape or curtain as desired, it may be that the strips and straps of the tape may be secured together at the same time that they are

secured to the curtain or drape by having the seams which secure the straps and strips together also secure the tape to the curtain or drape. The two seams whereby the preformed tape is secured to the curtain or drape may then be omitted.

The comparatively stiff material, such as buckram, of which the straps 30 are made, are not usually of a pleasing appearance and they may consequently be covered with a more sightly or desirable material, as soft woolen or cotton cloth, silk or any desired material. Fig. 9 shows one of the straps 30 covered with a covering 4, of any such desirable covering material and the other portions of buckram may be covered in a similar manner.

Referring now to Figs. 10 and 12 inclusive, there is therein shown a heading for a curtain or drapery comprising a tape formed of a ribbon or strip 42 of buckram and a cord or twine 43 of zigzag form and secured to the ribbon of buckram by sewing thereto along the lines 44 and 45. It will be observed that these seams pass through the longitudinal sections of the cord and secure the cord to the buckram ribbon or strip, but that between the seams 44 and 45 the sections of the cord are free of the buckram ribbon so that they may form means for holding the pleats and for suspending the curtain or drape upon a pole as will be hereinafter referred to.

The tape, comprising the buckram ribbon 42 and the cord 43 secured thereto as described, may be secured at the top of a curtain or drape 46 by means of sewed seams 47 and 48 passing through the buckram ribbon 42 and the curtain or drape 46.

In order to form the pleats (see Fig. 12) the buckram ribbon is bent outwardly about one of the transverse sections of the cord 43, for instance the section 49, and then bent inwardly again about the transverse cord section 50 to form the pleat 51 as shown in Fig. 12. Other pleats, as for instance the pleat 52, may be formed in a similar manner. In the formation of the pleats 51, the transverse cord sections or strips are brought adjacent to each other and one of the cord sections as 50 is passed through the loop of the other as 49, and through a loop

corresponding to the strap 50 at each of the pleats, a curtain pole or rod may be inserted.

With the arrangement of pole, straps or loops, one threaded within the other as described, the 5 pleats are prevented from spreading and at the same time the provision is made for the reception of a supporting pole.

As described above, the tape comprising the ribbon 42 and the cord 43 may be made up separately and then applied to a curtain or drape. It may be, however, that the cord, ribbon and drape may be simultaneously secured together by placing the cord, buckram ribbon and curtain in proper relative positions and then securing them all together by sewed seams 44 and 45. This will enable the seams 47 and 48 to be dispensed with.

While the invention has been illustrated in what are considered its best applications, it may have other embodiments without departing from its spirit and is not, therefore, limited to the structures shown in the drawings.

What I claim is:

The combination with a drape, of a ribbon extending along said drape, a zigzag cord superposed upon said ribbon, portions of said cord disposed longitudinally of the ribbon and portions disposed transversely, said drape, ribbon and cord being secured together, the longitudinal portions 25 of said cord being secured, but transverse portions of said cord being left free to form straps beneath which a curtain rod or pole may be inserted, said drape and ribbon being bent outwardly to form pleats about predetermined transverse portions of the cord whereby transverse portions of the cord spaced apart by one transverse portion are brought into proximity and one is protruded through the other.

ALEXANDER McD. HESS.
